BY *Victor J. Evans*

ATTORNEY

UNITED STATES PATENT OFFICE

JESSE M. GRIGG, OF CHICAGO, ILLINOIS

OSCILLATING HETERODYNE DETECTOR

Application filed September 10, 1928. Serial No. 305,035.

This invention relates to radio receiving apparatus and circuits and has for its general object the provision of an oscillating heterodyne detector circuit adapted to be interposed between any desired number of stages of radio frequency amplification and any desired number of stages of intermediate or beat frequency amplification.

The most important object of the invention is to provide a detector circuit embodying a resonant circuit inductively coupling the grid and plate circuits of the detector tube in contradistinction to providing an actual, direct or metallic connection.

Another important object of the invention is to provide a resonant circuit in which oscillation is sustained through the agency of the resonant system in action as relay in the inductive transfer of energy from the plate circuit to the grid circuit.

Another object of the invention is to provide an oscillating system comprising a resonant coil, a grid coil, and a plate coil, the resonant coil being both interposed between the grid coil and the plate coil and coupled to these in proper degree and direction of mutual inductance, and all three coils therefore being in such combined relationship that the electro-motive force relayed or transferred to the grid coil through the agency of the resonant coil exceeds the electromotive force of direct induction by an amount sufficient to sustain oscillation.

Another object of the invention is to provide a circuit of this character in which the arrangement is such that the input in series with the grid circuit or coils insures maximum transfer of potential, this input having one end at low potential, in fact at filament potential, therefore picking up only a minimum of stray capacitive energy and avoiding undesirable body capacity effect.

Another object of the invention is to provide a circuit of this character in which the provision of a high plate potential and a cor-

responding proper negative grid bias will keep the grid damping down.

Another object of the invention is to provide a circuit wherein the beat frequency is rectified into the system and in which a certain predetermined frequency, such as that in the ordinary wave band for broadcast reception may be heterodyned to an intermediate frequency, it being possible to provide a great difference between the signal and oscillator frequency, say even 500,000 cycles, the use of which frequency, as is well known, resulting in a one-spot super-heterodyne.

Another object of the invention is to provide a circuit arrangement of this character which will be simple to construct, easy to control, adjust or operate, positive in action, efficient in service, and a general improvement in the art.

To the attainment of the foregoing and other objects and advantages, the invention preferably consists in the circuit arrangement to be hereinafter more fully described and claimed, and illustrated in the accompanying drawing in which:

The figure is a diagram of the complete circuit arrangement.

Referring more particularly to the drawing, I have illustrated a combination of detector circuits in which the numeral 10 designates a detector tube having a grid 11, filament 12, and a plate 13.

There is nothing distinctive about the tube and it may be one of various types on the market for the purpose. The filament 12, is of course, intended to be heated by means of a suitable source of "A" current, regulation being effected by means of a suitable rheostat 14. The battery, or its equivalent, is not illustrated, inasmuch as it is well known. The circuit further includes inductances L1, L2, L3, L4, and L5. The inductance L1 may be the secondary of a radio frequency transformer 15 embodying the inductance L, or it may be a loop or other device,

there being no particular limitations in this respect.

The inductance L1 is shunted by a variable condenser C1 and is connected in series between the negative terminal of the "A" battery and the grid inductance L3 as clearly shown in the diagram. As it is desirable that the proper negative bias be applied to the grid lead, there is disclosed, diagrammatically, a "C" battery 16 interposed in series between the inductance L1 and the negative terminal of the "A" battery as is customary. The inductance L2 is shunted by a variable condenser C2 and is of course, connected with the negative terminal of the "A" battery as indicated. The inductance L4 is connected in series between the plate 13 of the tube 10 and the inductance L5 of the output, the latter being, of course, connected with the positive terminal of the source of "B" current. The inductance L5 is shunted by a by-pass condenser 17 and there is also provided a by-pass condenser 18 between the negative terminal of the "A" battery and the positive terminal of the "B" battery as is likewise customary.

The inductance L5 may be the primary coil of an intermediate frequency amplifier 19 or any other equivalent device, this being totally immaterial. The point is that there must be an output, and in a multiple stage circuit it is customary to provide two or more stages of intermediate frequency amplification of which the transformer 19 may constitute the first one.

In considering the entire detector circuit it will be noted that essentially it contains the resonant circuit C2, the inductance or coil L2 of which is inductively interposed between the grid coil L3 and the plate coil L4.

It is intended that the windings of the free ends of the coils be in opposite directions. In theory, the plate coil L4 transfers its energy to the resonant coil L2, which in turn induces an electro-motive force in the grid coil L3 and sustains oscillation. The input L1 in series with the grid coil L3 insures maximum transfer of potential, and with its low potential end at filament potential picks up a minimum of stray capacitive energy. A high plate potential and corresponding negative grid bias keep the grid damping down. The beat frequency is rectified into the system L5 in series with the plate coil.

The circuit scheme is applicable to either first or second harmonic operation. A frequency changer of this type is capable of being used in heterodyning to an intermediate frequency just below the broadcast band, or a difference between signal and oscillator frequency of about 500,000 cycles, the use of which frequency, as is well known, results in a one-spot super-heterodyne. Actually I have built two successful receivers using this type of frequency changer, one employing the

second harmonic principle and a beat frequency of 50 kilo-cycles, and the other using the first harmonic principle and a beat frequency of 500 kilo-cycles, showing that satisfactory operation may be had in any practical case, that is to say where loop and oscillator are not tuned too near to the same frequency.

Incidentally, the amplifiers employed in both the receivers may be of an ordinary or of a preferred type capable of individual and characteristic construction.

The advantages of this frequency changer are that the faults found in other types of one tube arrangements are absent. As near as can be determined, there is no reaction between the two tuned circuits, and since the rotors of both condensers are at filament potential there is no body capacity effect, no static pick-up, and furthermore gang condensers may be employed, the gang also tuning preceding radio frequency stages. Another advantage is that, using for example, the well known 201-A tube, the plate voltage is 90 and the grid bias 7½ volts negative, under which circumstances selectivity of the loop is not depreciated by grid damping as in the case of the usual two tube frequency changer. In conclusion, it may be said that inasmuch as I have experimented with all the well known types of frequency changers, besides several others of my own devising, the arrangement disclosed herein appears from every angle to be the most satisfactory of all.

It is thought from the foregoing that the construction, operation and advantages will be readily apparent to one skilled in the art without further explanation.

While I have shown and described the preferred embodiment of the invention, it should of course, be understood that various modifications may be resorted to without in any way departing from the spirit of the invention and I reserve the right to make such changes provided they constitute no departure from the scope of the subjoined claims.

Having thus described my invention, I claim:

1. In a stage of radio detection, an input inductance, an output inductance, a vacuum tube, a grid inductance connected in series with said input inductance and the grid of the vacuum tube, a plate inductance connected in series between the plate of the vacuum tube and the said output inductance, means for tuning said grid inductance, and an intermediate circuit embodying an inductance inductively coupled to said grid inductance and said plate inductance and having tuning means associated therewith for controlling local oscillations at a different frequency from the impulses in the grid circuit whereby heterodyning may be accomplished with a single vacuum tube.

2. In a stage of detection, the combination

of an input circuit, an output circuit, a grid circuit coupled to the input circuit and connected with the grid of a vacuum tube, an inductance connected in said grid circuit between the input circuit and the grid, an inductance connected with the plate of the tube and connected with the output circuit, and an intermediate resonant circuit embodying an inductance inductively coupled to the plate inductance and the grid inductance.

10 In testimony whereof I affix my signature.
JESSE M. GRIGG.
